Watson E. Coleman

Attorney

UNITED STATES PATENT OFFICE.

MERIT BENJAMIN WALKER, OF BLUM, TEXAS.

WELL-DRILL

Specification of Letters Patent. Patented July 4, 1916.

1,189,513.

Application filed January 26, 1916. Serial No. 74,390.

To all whom it may concern:

Be it known that I, MERIT B. WALKER, a citizen of the United States, residing at Blum, in the county of Hill and State of Texas, have invented certain new and useful Improvements in Well-Drills, of which the following is a specification, reference being had to the accompanying drawings.

This invention relates to certain improvements in well drills and it is an object of the invention to provide a device of this general character with novel and improved means whereby the operating cable may be connected with the upper end thereof in such a manner as to permit the upper end of the drill to be struck without liability of disengaging the cable from the drill.

The invention consists in the details of construction and in the combination and arrangement of the several parts of my improved drill whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be better understood, I will now proceed to describe the same with reference to the accompanying drawings, wherein—

Figure 1 is a view partly in elevation and partly in section illustrating an upper end or section of a drill constructed in accordance with an embodiment of my invention; Fig. 2 is a fragmentary longitudinal sectional view illustrating certain details of my invention as herein embodied, with the cable omitted; and Fig. 3 is a transverse sectional view taken through the device as herein embodied, with the cable omitted.

As disclosed in the accompanying drawings, 1 denotes the upper section or a well drill having its inner end provided with the threaded extension 2, whereby the same may be detachably engaged in a conventional manner with an adjacent well section, and said section 1 adjacent its outer end is provided with the elongated longitudinally disposed slot 3 having in communication with the upper end thereof the opening 4 dis-

posed longitudinally of the section 1 at its axial center and through which is adapted to be disposed an extremity of the cable 5.

The inner end of the slot 3 is provided with an inwardly disposed restricted extension or recess 6 provided at its inner end and at the axial center of the section 1 with the eye 7 through which the cable 5 is adapted to be threaded, and having its returned portion 8 secured to the portion of the cable 5 proper within the slot 3 by the clamps 9, preferably three in number as illustrated in the accompanying drawings, although I do not wish to be understood as limiting myself in this exact detail.

In the manner of attaching the cable 5 to the section 1 or upper end portion of a drill, it will be seen that the upper or outer end of the drill or section 1 may be struck in order to knock the drill loose when hung in a well without any danger of striking the clamps 9 or otherwise affecting the connection between the cable 5 and the drill or section 1. It will be readily perceived that in the event the cable 5 breaks at a point adjacent the eye 7, the upper clamp 9 will prevent the cable from being withdrawn through the opening 4, and it will also be perceived that in the event the cable 5 should be severed at a point above the drill, a grapple can be readily engaged within the elongated slot 3 in order to permit the drill being easily removed from within a well.

From the foregoing description, it is thought to be obvious that a well drill constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A drill having its outer end portion provided with an elongated slot and hav-

ing an opening in its outer end in communication with the outer end of the slot, and an eye arranged at the inner end of the slot.

2. A drill having its outer end portion provided with an elongated slot and having an opening in its outer end in communication with the outer end of the slot, the inner end of the slot being provided with a re-

stricted extension, and an eye arranged at the inner end of said extension.

In testimony whereof I hereunto affix my signature in the presence of two witnesses.

MERIT BENJAMIN WALKER.

Witnesses:

W. L. ROGERS,
B. V. ADAMS.
